UNITED STATES PATENT OFFICE.

PETER DE MATTIA, OF CLIFTON, NEW JERSEY.

COLLAPSIBLE CORE.

1,389,439.

Specification of Letters Patent. Patented Aug. 30, 1921.

Application filed June 8, 1920. Serial No. 387,414.

To all whom it may concern:

Be it known that I, PETER DE MATTIA, a citizen of the United States of America, and a resident of Clifton, county of Passaic, and 5 State of New Jersey, have invented a new and useful Improvement in Collapsible Cores used in the Manufacture of Shoes or Casings for Pneumatic Tires.

The object of the present invention is to 10 produce a collapsible core comprising a plurality of articulated sections so constructed and connected together as to afford a maximum of movement to the pivoted parts and thus greatly facilitate the removal of the 15 built-up shoe or casing without subjecting the same to distorting stress or pressure.

A further object of the invention is to provide a simple means to facilitate the withdrawal of the movable sections from the shoe 20 or casing, and to provide means whereby the key section may be entirely removed from a position of operative continuity and supported within convenient reach of the operator, thus affording a largely increased 25 movement of the pivoted sections.

To the above ends the present invention consists of the collapsible core and the devices and combinations of devices which will be hereinafter described and claimed.

30 The invention is illustrated in the accompanying drawings in which—

Figure 1 shows a top plan view of the collapsible core with the parts in operative continuity.

35 Fig. 2 shows a diametrical sectional view taken on the line 2—2 in Fig. 1.

Fig. 3 shows a view similar to Fig. 1 with the key section in the process of retraction.

40 Fig. 4 is a fragmentary detail, parts being shown in section, and parts in elevation, illustrating the manner of supporting the key section when removed from its connection with the chuck.

45 Fig. 5 is a fragmentary detail, parts being shown in elevation, and parts in section, illustrating the operation of the retracting device.

50 Fig. 6 is a fragmentary detail, parts being shown in elevation, and parts in section, illustrating the manner of connecting the retracting device with the chuck.

The core comprises a plurality of segmental sections, there being four such sections shown in the device as illustrated.

The segmental section 1 is a fixed section 55 and is connected by means of bolts 2 to the radial arms 3 and 4 projecting from a chuck 5. A swinging section 6 is pivotally connected as at 7 to the arm 4 and it is preferably provided with a brace 8 resting upon a 60 projection or rest 9 carried by the arm 4, as shown in dotted lines in Fig. 1, the brace 8 and the rest 9 helping to support the swinging section 6 in its pivotal movements.

A relatively short segmental section 10 is 65 pivotally mounted at 11 to a swivel 12 mounted to turn in a lug 13 formed upon the inner surface of the fixed section 1, the arrangement being such that the section 10 can swing inwardly about the pivot 11 and also 70 downwardly by reason of the pivotal action of the swivel 12 in its supporting lug 13.

The space between the free ends of the sections 6 and 10 is filled by a key section 14 which is provided with a shank or bar 15 75 projecting inwardly from its inner edge and arranged to have a sliding movement in a guideway 16 formed in the upper surface of the chuck 5 and beneath a brace 17 secured to the upper surface of the chuck 5 as by 80 means of screws 18 and spanning the guideway 16.

The chuck 5 is also provided with a swinging brace-bar 19 pivotally mounted upon a headed stud 20 and provided at its free end 85 with a hook or notch 21 arranged to engage beneath the head of the headed stud 22, the arrangement being such that the brace-bar 19 may be moved from the position shown in Fig. 1, spanning the guideway 16 and the 90 bar 15, to the position shown in Fig. 3.

Preferably this bar 19 is provided with a threaded bearing 23 receiving a threaded screw 24, provided with arms 25 whereby the same may be turned to cause its lower end 95 to engage the bar 15 and to hold it in its outward position with the segmental section 14 in operative continuity.

The arm or bar 15 is provided with sockets 26 extending along the longitudinal medial line of its upper surface, which sockets are positioned so that they may be engaged

by the lower end of the screw 23 to hold the key section, or be engaged by a retracting device which will now be described.

The retracting device is shown in Figs. 3, 5 and 6 and comprises a lever 27 which at one end is provided with a handle 28 and at its opposite end with a downwardly projecting stud 29.

The stud 29 is adapted to be removably engaged with any one of the sockets 30, 31 and 32 carried by the ears 33 formed integrally with the chuck.

The lever 27 carries a short link 34 pivotally connected thereto at 35 and which at 15 its outer end carries a down turned stud 36 which may be engaged with the sockets 26 of the arm 15, or with the sockets 37 formed in the ear 38 carried by the pivoted section 6, or with the socket 39 formed in the ear 20 40 of the section 10.

The chuck 5 may be mounted upon any suitable support, but preferably upon a rotary table 41 carried by a pivotal stud 42 mounted in the free end of the jack arm 25 43 whereby the table 41 may freely turn about the pivot 42.

The table will be preferably provided with notches 44 arranged to be engaged by a latch 45 carried by the jack arm 43.

30 The brace 17 is provided with an extended projection 46 in which is formed an opening 47 whereby when the arm 15 shall have been moved backwardly it may be passed downwardly into the opening 47 to support 35 the segmental section 14 in a convenient position for the operator and out of the path of movement of the swinging parts.

In order to prevent the segmental section 14 from passing downward too far when 40 supported by the bracebar 17, it is provided with a stop 48 having a hooked end 49 arranged to engage over the bar at the outer end of the opening 47 as shown clearly in Fig. 4 of the drawings.

45 In operation, assuming the parts to be in operative continuity as shown in Fig. 1, the operator first retracts the segmental section 14, using for this purpose the retracting device which is positioned as shown in Fig. 3 50 with its stud 29 in engagement with the socket 30 in the ear 33 and with the stud 36 of the link 34 inserted in one of the sockets 26 of the arm 15. By engaging the stud 36 in the sockets progressively the lever 27 55 may be swung in the direction of the arrow as shown in Fig. 3 to draw back the segmental section 14 as indicated in Fig. 3.

After the segmental section 14 has been retracted it is lifted out of the plane of the 60 core and shank 15, and allowed to slide downward so that stop 48 will rest on projection 46 of the brace 17. The pivotal section 10 is then withdrawn from the casing or shoe and for this purpose the retracting

device is engaged with the socket 39 in the 65 ear 40 causing it to swing on pivot pin 11.

Having withdrawn the pivotal section 10 out of the casing, it is pushed downward out of the plane of the core by swinging simultaneously on pivot 11 and swivel 12.

70 Preliminary to this retraction of the segmental section 14 the pivoted brace 19 has been moved to the position shown in Fig. 3.

The pivotal section 6 is withdrawn from the casing by engaging the retracting device with the socket 30 of the ear 33 and with socket 37 of ear 38, causing it to swing on pivot pin 7 out of the casing.

When the core sections are in the position above described the tire casing can be removed by forcing it upward and out of the plane of section 10.

80 The meeting faces of the free ends of the sections 6 and 10 and of the key section 14 will preferably be provided with complementary engaging devices such as the projections 50 and notches 51 at the outer circumference, and projections 52 and notches 53 at the inner circumference.

85 Also the meeting faces of the section 6 and section 1 will preferably be provided with the interlocking tenon and groove 54 shown in dotted lines in Fig. 1, and the meeting ends of the sections 10 and 1 with the interlocking projection and groove 55 shown in dotted lines in Fig. 1.

90 Having described my invention, I claim:

1. A collapsible core comprising a plurality of segmental sections, one of said sections being a key section, a shank carried by said key section, a chuck supporting said sections, a guideway in said chuck to receive the shank of the key section, and a brace bar spanning the guideway at its rear end.

105 2. A collapsible core comprising a movable segmental section, a chuck supporting the said section, a retracting device and complementary engaging means carried by the segmental section, chuck, and the retracting device, whereby the retracting device may be 110 removably connected to the chuck and the movable segmental section for retracting said segmental section and collapsing the core.

115 3. A collapsible core comprising a plurality of segmental sections, a chuck supporting the said sections, one of the said sections comprising a key section provided with a shank having a sliding movement in the chuck, and a swinging clamping device 120 for locking the shank in its engagement with the chuck.

125 4. A collapsible core comprising a plurality of segmental sections, one of said sections comprising a key section, a sliding shank carried by the key section and engaging a guideway in the chuck, and a support for said shank and key section at the

rear end of such guideway when removed from the chuck.

5. A collapsible core comprising a plurality of segmental sections, one of said sections being a key section and two of said sections being pivoted to swing inward and outward and also to be positioned below the

plane of operative continuity of the core, a sliding removable connection between the key section and the chuck, and a brace bar 10 at the rear end of the sliding connection positioned to receive the shank and support the key section when removed.

PETER DE MATTIA.
